COMBINED SUPPORT AND CONTAINER FOR TOOTHBRUSHES

Charles S. Fentules, 15 Illinois Ave.,
Youngstown, Ohio 44505

Filed Mar. 3, 1975, Ser. No. 554,914

Term of patent 14 years

Int. Cl. D23—02

U.S. Cl. D6—94

FIG. 1

FIG. 3

FIG. 1 is a top plan view of a combined support and container for toothbrushes showing my new design;

FIG. 2 is a front elevation thereof; and

FIG. 3 is a side elevation thereof.

I claim:

The ornamental design for a combined support and container for toothbrushes, as shown.
